UNITED STATES PATENT OFFICE.

FREDERICK HACHMANN, OF ST. LOUIS, AND HENRY C. SICKMANN, OF MARTHASVILLE, MISSOURI, ASSIGNEES OF ONE-FIFTH TO JOHN A. BLEVINS, OF ST. LOUIS, MISSOURI, AND TWO TWENTY-FIFTHS TO JOHN H. BIERBAUM, OF MARTHASVILLE, MISSOURI.

COMBINED TIE PLATE AND RAIL FASTENER.

Application filed January 30, 1922. Serial No. 532,668.

To all whom it may concern:

Be it known that we, FREDERICK HACHMANN and HENRY C. SICKMANN, citizens of the United States, and residents of the city of St. Louis and State of Missouri and city of Marthasville, county of Warren, and State of Missouri, respectively, have invented certain new and useful Improvements in Combined Tie Plates and Rail Fasteners, 5 of which the following is a specification containing a full, clear, and exact description, reference being had to the accompanying drawings, forming a part hereof.

Our invention relates to improvements in combined tie plates and rail fasteners, and has for its primary object a device which will not only act as a tie plate, but also will secure the ends of rails together, without the employment of any bolts.

10 A further object is to construct a combined tie plate and rail fastener, in which the wear on the fastening means is automatically taken care of.

15 A further object is to construct a combined tie plate and rail fastener, in which the meeting ends of the rails are held against separating, and in which wedges are utilized to prevent lateral movement of the rails. The wedges being automatically held to prevent 20 this lateral movement.

In the drawings,

Fig. 1 is an end elevation of our device, showing the same secured to a rail, the rail being in section.

25 Fig. 2 is a top plan view.

Fig. 3 is an end view of the tie plate.

Fig. 4 is a top plan view of the same.

30 Fig. 5 is a longitudinal section taken on the line 5—5 of Fig. 4, viewing the same in 40 the direction of the arrow.

Fig. 6 is a top plan view of one of the wedge members.

Fig. 7 is an end view of the same.

45 Fig. 8 is an end view of one of the fish plates.

Fig. 9 is a top plan view of the same.

Fig. 10 is a side elevation of the same.

Fig. 11 is a plan view of the locking key.

Fig. 12 is a side elevation.

Fig. 13 is an end elevation of a modified 50 form of tie plate, with the rail in position.

Fig. 14 a top plan view of the same.

Fig. 15 is a side elevation of the same.

In the construction of our device we employ a tie plate consisting of a base 20. 55 Formed integral with the base 20 are wedge bases 21. These wedge bases extend longitudinal of the plate 20, and are parallel and spaced apart from each other. The ends 22 are lower than the ends 23, so that the bases 21 are inclined longitudinally and in opposite directions. Formed integral with the bases 21 are ribs 24. These ribs are also inclined, their ends 25 being lower than the ends 26. These ribs are arranged parallel 65 to each other and extend diagonally to the bases 21. The inner walls of the ribs 24 are undercut, as indicated by the numeral 27. Formed integral with the bases 21 are projections 28, which extend toward the center of the plate. These projections are formed at opposite ends of the bases 21, and are of the same height, as that end of the base at which they are located. Formed 70 integral with the plate 20 and bases 21, are projections 30, which have a pocket 31 formed therein. These projections are formed adjacent the end 23 of the bases 21 and are for the purpose of receiving the locking keys 32, which locking keys are provided with a projecting lug 33, which lug has its inner face beveled, as indicated by the numeral 34, (see Fig. 12) and in order 75 to limit the depth of insertion of the key 32 in the pocket 31, the key is provided with an offset or shoulder 35. Placed between the projecting portions 28 are fish plates 36. These fish plates are provided with a wedge base 37. The wedge base 37 being thicker 80 at the end 38, than at the end 39. Its inclination corresponding with that of the wedge bases 21. The outer vertical base of the fish plate 36 is undercut, as indicated by the numeral 40, this undercut portion being for the purpose of preventing the wedge 41 85 from raising when driven home. The wedge 41 is so constructed as to have its end 42 narrower and thinner than the end 43, while

90 95

its side walls are beveled, as indicated by the numerals 44 and 45. The bevel 45 is adapted to contact with the undercut portion 40 of the fish plate 36, while the bevel 44 engages with the undercut wall 27 of the projections or ribs 24. The end 43 of the wedge 41 is provided with a pocket 46 for the purpose of receiving a spring 47. This spring is inserted in the pocket 46, and is held under tension by means of the locking key 40, thus preventing the wedges 41 from working out. The fish plates 36 are provided on their inner faces with lugs 48. These lugs are adapted to fit in openings 15 formed in the web of the abutting rails 49, and prevent the rails from being pulled apart or creeping. The openings into which the studs 48 fit are present in all rails, as they are at present utilized to secure the 20 ordinary fish plate to the rail by means of bolts passing therethrough.

In our device, however, the lugs or studs 48 enter alternate holes. In order to prevent the ribs 24 from breaking off or spreading, we form ribs or braces 50, which are formed integral with the base and with the ribs 24. It is of course to be understood that the tie plate or base 20 is to be secured to railroad ties in any well known manner.

30 The method of applying our device is as follows:

The base 20 is first secured to the ties and the rails 49 placed thereon. The base flanges extending through the open space between the projections 28. The fish plates 36 are then placed in position, the wedge base 37 extending only between the projections 28, which are formed integral with the wedge base 21. This prevents the fish plates from shifting, and also prevents creeping of the rails. After the fish plates have been inserted, the wedges 41 are placed in position and driven home, and due to the inclined faces of the wedge bases and of the wedges, 45 the fish plates are forced tightly against the web of the rail, and also tightly against the base flanges. After the wedges have been driven home, the springs 47 are inserted in the pockets 46. The locking keys 50 32 are placed within the pockets 31 and driven down. This allows the springs to ride over the lugs 33, due to the inclined face 34. Each locking key is now held against accidental removal by means of the tension of the spring, and in order to remove the key it is necessary to compress the spring sufficiently to clear the projection or lug 33. The spring 47 is made stiff enough so that the employment of a sufficient tool to compress the 55 spring, and in order to remove the key it is necessary. This precludes the danger of unauthorized persons removing the locking key and allowing the wedges to work out, and wreck the train.

By the use of our device the rails are held 60 from creeping. Any side movement of the

abutting ends of the rails is eliminated. There are no bolts to elongate or nuts to jar loose, and any expansion of the base 20 is taken care of by the springs 47, which will tend to force the wedges 41 in tighter. 70

In our modified form, the base 51 is constructed practically identical with the base 20. With this exception, the ends 52 instead of being provided with a pocket 31, are provided with projecting lugs 53, while the fish 75 plates 36 also have extensions 54 formed thereon. These projections are screw threaded for the purpose of receiving bolts 55, which secure the yoke 56. This yoke is provided with a screw threaded boss 57, 80 through which passes a bolt 58. This bolt is provided on its inner end with a pocket 59 which receives one end of a coil spring 60, the other end of the coil spring being seated in the pocket 61 formed in the wedges 85 62.

By the use of this device, the tension on the wedge members 62 can be regulated, and increased or decreased at will, while the removal of the wedges is simplified by the fact that the spring can be removed by the use of a wrench, or the entire yoke may be removed by a similar process, but other than this, the construction of the various parts, and the operation and purposes are the same 95 as in the previously described device.

Having fully described our invention, what we claim is:

1. A combined tie plate and rail fastener comprising a base, inclined wedge bases 100 formed integral therewith, under cut ribs formed integral with said wedge bases, fish plates having integrally formed wedge bases, said fish plates adapted to be seated on either side of the rail, wedges adapted to be inserted under the under cut ribs for locking the fish plates against the rail, and resilient means for holding the wedges against retrograde movement.

2. A combined tie plate and rail fastener 110 comprising a base, inclined wedge bases formed integral therewith, under cut ribs formed with said wedge bases, fish plates having integrally formed wedge bases, said fish plates adapted to be seated on either 115 side of the rail, wedges adapted to be inserted under the under cut ribs for locking the fish plates against the rail, resilient means for holding the wedges against retrograde movement, and a locking key for holding the 120 resilient means in position.

3. The combined tie plate and rail fastener of claim 1, in which the wedge members are provided with pockets for receiving one end 125 of the resilient means.

4. The combined tie plate and rail fastener of claim 2, in which the wedge members are provided with pockets for receiving one end of the resilient means.

5. The combined tie plate and rail fastener 130

comprising a base, inclined wedge bases formed integral therewith; undercut ribs formed integral with said wedge bases, fish plates having integrally formed wedge bases, 5 said fish plates adapted to be seated on either side of a rail, wedges adapted to be inserted under the undercut ribs for locking the fish plates against the rail, pockets formed integral with said base, locking keys adapted

to be inserted in said pockets, and a coil 10 spring inserted between the wedge and locking key, said spring adapted to tend to force the locking wedges forward, so as to compensate for jolting and wearing.

In testimony whereof, we have signed our 15 names to this specification.

FREDERICK HACHMANN.
HENRY C. SICKMANN.
